METHOD AND APPARATUS FOR ROLLING SHEET-LIKE MATERIAL.

Application filed October 24, 1927. Serial No. 228,176.

This application is a continuation in part of our application, Serial No. 103,264, filed April 20, 1926.

This invention relates to the rolling of sheet-like material and is particularly useful for the rolling of long lengths of wide sheets, although it is also of great value in the rolling of plates, strips and other products of substantially uniform thickness. In particular it is adapted for the application of very heavy drafts to wide, thin sections of metal. It provides a mill which may be operated at high speed and further, provides a continuous rolling mill for rolling metal strips of practically unlimited length, and of a ratio of width to thickness which is comparable only to sheet metal as distinguished from plates and strips as produced in the past.

Except for recent developments in which accuracy of control of the shape of roll passes has made it possible to depart therefrom, it has been the practice in the metal rolling industry to produce sheet metal by the process of rolling a pair of sheet bars in a preliminary step, into rough plate, then heating the plates and rolling them in a pack in a mill with two rolls (two high), with such doubling, increasing of the layers in the pack, and reheating as is called for in the opinion of the roller in charge of the mill.

In the rolling of strips, in which the length of the piece is not a limitation, as in pack rolling, there has been a considerable development in the use of continuous mills operating on the piece when both hot and cold, but the results have not been satisfactory from the point of view of producing sheet metal in strip form. It has been the universal experience of workers in the strip rolling art, which has always been distinct from the sheet rolling art, that in the greater widths of product, reductions to thinness comparable with sheet metal has not been practical. Expressed in other words, nothing approaching the ratio of width to thickness of sheet metal has been commercially practical to produce on the strip mills of the past.

In rolling by the usual methods and with the usual mills great difficulty has always been experienced due to several factors, the most important of which are changes in shape of the rolls due to the roll neck heating, and changes in the setting of the rolls due to wear of the brasses. The pressures

developed between the necks and the brasses are so high that sufficient heat is generated to swell the bodies of the rolls irregularly and thus adversely affect the contour of the piece. This high pressure also results in very rapid wear of the brasses. This wear may be as high as one sixteenth of an inch per hour on each brass. This condition is so bad that in strip mills it has been the practice to gauge every strip and to almost continually adjust the screw downs in an effort to maintain uniform gauge. Even with all precautions irregularities in gauge occur in the finished product, the gauge frequently varying from end to end of a single strip.

Our mill is adapted to the continuous rolling of strip metal, with a sheet ratio of width to thickness, the product being termed for convenience hereinafter as a strip sheet. Our mill is effective for reduction of metal in sheet or strip form, at high speed, with radical reductions in each pass, and by a continuous rolling process.

By a "continuous rolling process" we refer to a rolling process in which the piece passes from one stand of rolls to the next, receiving one pass in each stand, as distinguished from being repassed through the same stand. In such continuous rolling process the piece may be engaged but by a single roll stand at a time, or it may be engaged by two or more successive roll stands at the same time.

The use of a four high mill having rolls to engage the piece which have small diameters relative to the two outer rolls, which serve to back up the smaller rolls and give them rigidity against excessive springing, is more or less familiar in the art, although not in continuous rolling or strip processes. Such mills give greater reductions with the same amount of force exerted, than do mills having but two rolls having the same strength as the sum of the strengths of one small diameter roll and one large diameter one, because of the reduced area of metal in surface engagement with the small rolls, as compared to the area which is engaged, if the rolls are very large.

In high speed mills which are required for use in a continuous process, great difficulty is experienced in driving the rolls, particularly in the last few stands. The last stands pass a very long strip in the same length of time as a much shorter strip was passed through the first few passes. This requires high

speed whether the piece is hot or cold, and high speed is also required in hot rolling so as to avoid intermediate heating. When the piece is thin and wide, it has a very large area in proportion to its mass and radiates its heat very rapidly, and no time can be lost in hot rolling.

We provide for driving the small diameter or working rolls and allow the larger 10 backing rolls to revolve by frictional contact with these smaller rolls. The driving of the working rolls gives a positive gripping of the piece, and at the same time balances the lateral pressure on the working rolls. This 15 lateral pressure is in a direction longitudinally of the piece being rolled and in a direction opposite to the direction of rolling. By driving the working rolls this lateral pressure is substantially balanced out and 20 wear on the brasses of the working rolls is materially reduced. The driving of the working rolls is also of advantage in that it eliminates any necessity for maintaining exact ratios of diameters between the backing 25 rolls, such as would have to be maintained if the backing rolls were driven positively and the working rolls were driven by friction therefrom.

From the point of view of thin strip rolling, it should be pointed out that a slight 30 defect in the true contour of the pass between the rolls of a mill, when the piece is between them, will result in reducing the thickness of the piece more at one point than another, 35 and thus increasing the length more along one line than another. In a long piece such as a strip, the result of increasing the length more along one line than another is much more serious than in the rolling of 40 short pieces because the metal being thin, cannot flow laterally, and the defective zone continues to increase in length through the whole body of the strip, in a cumulative manner, thus twisting the piece if the increase in 45 length is at one side, which twist is termed "camber", or distorting it if it is at both sides, or buckling the piece if it is in the middle.

It is thus of particular importance in 50 strip rolling, and of even more importance in continuous strip or strip-sheet rolling, to control the shape of the roll pass very accurately so as to reduce all portions of the metal proportionately.

The wider the piece being rolled, and the 55 thinner its cross section, the more imperative becomes the accuracy of the roll passes, as will be obvious when the great pressures required to make an effective reduction are considered, and the increased forces tending to spring the rolls out of shape while acting on wide metal as compared to narrow metal.

It is necessary in a continuous rolling process for strip sheets to reduce the metal in any 60 one stand so that it is of proper cross sec-

tional size and shape for the succeeding stand. Unless this condition is obtained, the continuous rolling process becomes impractical.

The increased tendency of the rolls to 70 spring out of shape under the heavy reductions employed, with its consequent difficulty in controlling the contour of the several passes, may be substantially eliminated by utilizing mill stands having at least one, and 75 preferably two working rolls of relatively small diameter, and backing rolls of relatively large diameter for the working rolls. The working rolls have a relatively small area of contact and the backing rolls may be 80 made sufficiently large to resist bending. But a mill of this character is still objectionable because of roll neck heating. The necks of the backing rolls carry the load and if they were equipped with ordinary brasses 85 sufficient heat would be generated to swell the backing roll bodies irregularly, and this condition would be reflected through the working rolls and adversely affect the contour of the pass, rendering control impossible. On this account it is impossible to roll strip sheets continuously in mills equipped 90 with ordinary brasses, even if they were four high, and even in single stands the speed of rolling must be exceedingly slow. 95

Instead of the usual brasses we provide anti-friction bearings for the necks of the backing rolls. The provision of anti-friction bearings insures maintenance of a temperature at the backing roll necks sufficiently 100 low to substantially prevent distortion of the contour of the pass and consequent buckling or wrinkling of the product.

It is necessary to depart from customary 105 mill design in order to accommodate the anti-friction bearings. The necks of the backing rolls must be made strong enough to withstand the spreading force, and our experience has been that when anti-friction bearings of sufficient size to carry the heavy 110 load in a relatively wide mill are designed for these necks, they require a greater space than is available if the backing roll bodies are dimensioned purely with reference to the beam strength required. In order to accommodate these large roller bearings, it is necessary to materially enlarge the diameter of the backing rolls relative to the working rolls over their diameter if calculated as beams. By using relatively small working 115 rolls so as to limit the spreading force and relatively large backing rolls so as to permit of using adequate anti-friction bearings, it is possible to limit roll neck heating, thus permitting the accuracy of control necessary for continuous rolling processes. 120

One of the advantages of four high mill design is that the backing rolls can be given almost any desired diameter without affecting the power required to operate the mill, 130

since the engagement with the piece is a function of the working rolls only. We are accordingly not limited in the size of our backing rolls, and are able to employ adequate anti-friction bearings in our mills, whereas in wide two high mills for rolling material of substantially uniform thickness there is not sufficient space to accommodate anti-friction bearings which will carry the load; this is because in the rolls of a two high mill the necks of the rolls would have to be so large in order to resist the spreading force that there would be insufficient space between them for adequate roller bearings to be mounted.

It should be noted further that from the point of view of accuracy of reduction, so important in the rolling of strip and particularly strip sheets, the absence of wear in the bearings of the backing up rolls, which is provided for by the anti-friction bearings in our mill, permits us to produce a product of a quality which would be impractical if the usual type of bearings were employed. The wear of a very small amount in the bearings of a mill will vary the reduction imparted to the strip and as the wear would not be uniform, the use of the usual brasses in a mill subjected to the heavy duty and high speeds called for in the production of strip sheet would be practically impossible.

In practice, we prefer to operate several stands in series so as to carry out a continuous rolling process. The material runs straight and true and buckling or wrinkling of the strip sheet is avoided. The rolling may be carried on hot or cold, the anti-friction bearings functioning in either case to prevent distortion of the rolls, due to heating of the roll necks, and inaccurate rolling due to wear on the bearings.

Anti-friction bearings also serve to materially reduce the power required. They are therefore effective not only for permitting the continuous rolling of high quality sheet material, but also for effecting material economies in the operation of the several stands.

Mills embodying only single stands are highly useful in rolling operations requiring heavy reductions of metal, either hot or cold. We will describe our invention with relation to a mill having but two backing up rolls, termed by us a four high mill, but it will be understood that the principles of our invention may apply to mills having more than two backing up rolls.

In the accompanying drawings illustrating the present preferred embodiment of our invention as applied to hot rolling,

Figure 1 is a diagrammatic view of a mill for a continuous rolling process employing four high millstands having anti-friction bearings,

Figure 2 is a top plan view partly broken

away of one of the millstands showing its drive in more detail,

Figure 3 is a front elevation partly broken away of a single stand,

Figure 4 is a top plan view of the mill 70 stand shown in Figure 3,

Figure 5 is an end elevation thereof,

Figure 6 is a section partly broken away, taken on the center line of the mill and showing the anti-friction bearings for one 75 of the backing up rolls,

Figure 7 is an end elevation to enlarged scale showing the manner of supporting the working rolls, and

Figure 8 is a horizontal section taken on 80 the line VIII—VIII of Figure 7.

Referring first to Figure 1 there is shown a series of slab heating furnaces F, each discharging onto a roll table 2. The roll table carries the slabs successively to a two-high mill 3 where the first reduction is effected. After leaving the mill stand 3 the slab is carried by table rolls 4 to edging rollers 5 and thence to a millstand 6. The stand 6 comprises working rolls having backing rolls of larger diameter, these backing rolls being provided with anti-friction bearings.

The slab is delivered from the stand 6 to a roll table 4^a and then passes through edging rolls 5^a and a second four high stand 6^a. After leaving the stand 6^a the slab is carried by table rollers 4^b to edging rollers 5^b and another four high stand 6^b.

The several stands are driven by independent motors 7, 7^a, and 7^b through reducing gears 8, 8^a and 8^b. The reducing gears each drive pinion stands 9 from which power is taken to both of the working rolls in each of the four high stands through spindles 10.

The several stands 6, 6^a and 6^b are run at progressively increasing speeds so that if a piece of material should be long enough to extend through two successive passes at one time the rolling will be properly effected. In operation, the material will not ordinarily be passing through more than one of the stands 6, 6^a or 6^b at one time, although if a particularly long slab is employed the stands 6^a and 6^b may both engage the metal 115 at once.

It will be noted that the gear sets 8, 8^a and 8^b effect successively smaller speed reductions between the corresponding motors and their pinion sets. This permits of securing the desired variation in the speed of the rolls in the several stands with correspondingly less variation in motor speed.

The material is delivered from the stand 6^b onto a roll table 11. The rollers of this table, instead of being placed at right angles to the center line, make an acute angle with a line perpendicular to such center line. When the material is fed forward by the rollers 11, this arrangement of rollers causes

it to travel sidewise as well as forward. The sidewise movement carries it against a side guide 12 so that the material is properly aligned to enter the succeeding stands. This 5 particular form of roll table is no part of the present invention, and is more particularly described and claimed in the copending application of Florence C. Biggert, Jr., Serial No. 236,409, filed November 29, 1927.

10 From the roll table 11 the material passes through successive stands 13^a, 13^b, 13^c, 13^d, 13^e and 13^f. Each stand comprises two working rolls each having a backing roll of larger diameter. The backing roll necks are 15 provided with roller bearings. Each stand is driven by an independent motor through gearing and pinions similar to the drive provided for the stands 6, 6^a and 6^b. One of these drives is shown in enlarged diagram 20 in Figure 2.

The stands 13^a, 13^b, 13^c, 13^d, 13^e and 13^f are operated at successively higher speeds and form a continuous mill in which the material is subjected to successive reductions and issues as a long, straight strip sheet.

30 The material produced by the mill is so thin and wide that its direction of travel between stands cannot be controlled by side guides. The anti-friction bearings provided for the necks of the backing rolls are effective for maintaining the contour of the backing rolls within such limits that the proper direction of the material from one stand to another is not disturbed. The stands are arranged so that material is fed from one stand to the other in a substantially direct line.

Figures 3 to 8 inclusive show one of the 40 four high stands in detail. Each stand comprises working rolls 15 backed by larger rolls 16. As above stated, power is supplied to the rolls 15 through spindles 10. The wobbler connections are shown at 17 in 45 Figure 3.

Each backing roll 16 is provided with roller bearings indicated generally by the reference characters 18 and 19. The backing rolls are not positively driven, but are 50 nevertheless provided with drive connections 20 which are used when the rolls are turned, or in case they are redressed.

The bearings 18 and 19 each have a spacer ring 21 abutting the roll body. The inner race 22 fits against this ring. Each outer race 23 is carried in a case 24 which fits in a window of the mill housing 25. Bearing rollers 26 spaced from one another by cages 27 lie between the inner and outer races. 60 The outer race of the bearing 18 bears at its inner end against a shoulder 28 formed in the case 24 and is held in place by a spacer 29 having an inner sleeve portion 30 connected by ribs 31 to an outer flange portion 32. This outer flange portion is secured by

studs 33 to the case 24. The inner race of the bearing 18 is held in place by a spacer ring 34. The backing roll necks are recessed near their outer ends to receive half rings 35. These half rings are threaded on their outer faces to receive a retainer 36. The retainer is screwed tightly against the spacer ring 34 and is held in place by one or more screws 37 extending through the retainer rings 36 into the spacer 34.

70 Felt rings 38 are provided between the rings 21 and the case 24 and between the spacer ring 34 and the flange 32 to prevent ingress of dirt.

Each bearing 19 is designed to resist end thrust as well as radial load. The provision of anti-friction means for resisting end thrust is relatively less important than the provision of anti-friction means for taking the radial load. However, the space provided makes the hereinafter described end thrust bearing easy of application.

80 A spacer ring 39 fits around the roll neck and abuts the inner race 22 of each bearing 19. A thrust ring 40 fits against the spacer ring 39 and a spacer ring 34^a lies outside the thrust ring 40. The spacer ring 34^a is held in place in exactly the same manner as is the spacer ring 34 of the bearing 18.

85 On either side of the thrust ring 40 there are provided thrust resisting rollers 41 carried in cages 42. Outer thrust rings 43^a and 43^b are provided. The thrust ring 43^a bears against the race 23, and the thrust ring 43^b is held in place by a flange 32^a. The flange 32^a is held in place by studs 33.

90 This thrust bearing definitely positions one end of the backing roll. It will be noted from Figure 6 that the bearing 18 permits end play and thus takes care of longitudinal expansion or contraction of the roll.

95 Figures 7 and 8 show the bearings for the working rolls 15. These bearings need only resist the sidewise thrust and ordinary brasses suffice for this. The apparatus shown in Figures 7 and 8 provides a convenient way of aligning the working rolls.

100 The lower working roll 15 rests on its backing roll 16 and brasses 44 engage all its necks or opposite sides. The brasses 44 at each end of the roll are supported by a hollow casting 45. This casting fits in the window of the mill housing and is held in place by clamp fingers 46.

110 The upper working roll is similarly mounted, except that it is additionally provided with brasses 47 below the necks. The brasses 47 provide a bearing support for the upper roll when the mill is stationary or is running idle.

115 The brasses 44 engage the ends of the working roll bodies as shown in Figure 8. These brasses are backed by plates 48 whose inner ends engage shoulders 49 formed on the brasses 44. Clamping fingers 50 carried

125

130

by studs 51 in the castings 45 engage the outer ends of the plates 48. The fingers are adjustable by nuts provided on the studs 51, so as to take up end play in the working rolls.

5 A lateral adjustment of the working rolls is also provided. Wedges 52 lie on either side of each working roll neck. These wedges are inside the hollow castings 45 and are adjustable toward or away from the 10 center of the mill by bolts 53 which extend through openings in the hollow castings, and are provided with adjusting nuts 54. Wedge blocks 55 lie on either side of each wedge 52. The outer wedge blocks are stationary, but the inner ones bear against the plates 48 and transmit force from the wedges. By adjusting the wedges on opposite sides of a roll neck, one inwardly and the other outwardly, a side wise adjustment 20 of that end of the roll is effected.

The lower backing roll and its working roll are not arranged for vertical adjustment, the casings 24 resting on the housings 25 at the bottoms of their windows. The 25 upper rolls are adjustable to permit of rolling different gauges. This adjustment is effected by screws 56 operated through gearing by screw-down motors 57.

Balance springs 58 are provided for the 30 upper rolls. These springs rest on forks 59 formed in the mill housings and are connected through lift rods 60 to slides 61. These slides have ledges 62 (Figure 7) at their bottom ends, which ledges engage the 35 castings 45 for the upper working rolls.

We have shown and described the preferred embodiment of our invention, but it will be understood that it is not limited to the form shown, but may be otherwise embodied or practiced within the scope of the 40 following claims.

We claim:

1. In the method of rolling thin sheet or strip material in a mill having working rolls, and backing rolls, of larger diameter, for the working rolls, the steps consisting in limiting the rise in temperature of the backing roll necks to such a point that variations in the contour of the backing rolls 45 are controlled within such limits as to substantially prevent buckling or wrinkling of the thin material passed between the working rolls.

2. In the method of rolling thin sheet or strip material in a mill having working rolls, and backing rolls, of larger diameter for the working rolls, the steps consisting in supplying rolling power through the working rolls and limiting the rise in temperature 55 of the backing roll necks to such a point that variations in the contour of the backing rolls are controlled within such limits as to substantially prevent buckling or wrinkling of the thin material passed between the working rolls.

3. A mill for rolling material of substantially uniform thickness, comprising at least two working rolls provided with backing rolls of larger diameter, the backing rolls having necks of sufficient size to withstand 70 the rolling pressure, and anti-friction bearings for said backing roll necks, the diameter of the backing roll body relative to the diameter of the working roll being such as to permit of using anti-friction bearings of 75 sufficient size to withstand the rolling pressure.

4. A mill for rolling material of substantially uniform thickness, comprising working rolls provided with backing rolls of 80 larger diameter, the backing rolls having necks of sufficient size to withstand the rolling pressure, anti-friction bearings for said backing roll necks, the diameter of the backing roll body relative to the diameter of the 85 working roll being such as to permit of using anti-friction bearings of sufficient size to withstand the rolling pressure, a working roll having a neck extending between the anti-friction bearings of the backing rolls, 90 and means for supplying rolling power through the working roll neck.

5. A mill for rolling material of substantially uniform thickness, comprising working rolls having backing rolls of larger 95 diameter, the backing rolls having necks of sufficient size to withstand the rolling pressure, and anti-friction bearings for said backing roll necks, the diameter of the backing roll body relative to the diameter of the 100 working roll being such as to permit of using anti-friction bearings of sufficient size to withstand the rolling pressure, at least one of said anti-friction bearings being so formed as to oppose endwise thrust of the 105 backing roll.

6. In the method of rolling thin sheet or strip material in a mill having working rolls provided with backing rolls of larger diameter, the step consisting in maintaining the 110 temperature of the backing roll necks below a point where expansion of a backing roll body induced by heat in the roll necks causes variation and consequent buckling or wrinkling of the product.

7. A mill for rolling thin strips or sheets, having working rolls and backing rolls of larger diameter, the working rolls being substantially uniformly spaced apart and defining a pass of such width and thinness 115 that material heating of the backing roll necks would cause such unequal expansion of a backing roll body as would distort the pass sufficiently to cause buckling or wrinkling of the thin product, and anti-friction 120 bearings for the backing rolls, whereby the temperature of the backing roll necks is maintained sufficiently low to substantially obviate such unequal expansion as would cause such buckling or wrinkling.

8. A rolling mill for material of substantially uniform thickness, the mill being of such width that the available space in a two high mill of the same width would prevent the use of roller bearings of the necessary load carrying capacity, comprising large backing rolls with necks, intermediate working rolls, means for driving the working rolls, and anti-friction bearings for the backing rolls, the anti-friction bearings having outer races encircling the necks, the intermediate working rolls being of sufficiently small diameter to reduce the spreading force in the mill to such point that the anti-friction bearings employed require a smaller space than those which would be required in a two high mill of the same width, whereby the outer races of the bearings for the backing rolls are sufficiently spaced apart to allow room for the driving means.
9. A continuous mill for rolling material of substantially uniform thickness, comprising a plurality of stands having working rolls provided with backing rolls of larger diameter, the backing rolls having necks of sufficient size to withstand the rolling pressure, and anti-friction bearings for said backing roll necks, the diameter of the backing roll bodies relative to the diameter of the working rolls being such as to permit of using anti-friction bearings of sufficient size to withstand the rolling pressure, the stands being so arranged that during at least a portion of the rolling operation the material is being rolled simultaneously in at least two stands.
10. In the method of rolling material of substantially uniform thickness in a mill comprising a plurality of stands having working rolls provided with backing rolls of larger diameter, the steps consisting in passing a piece of material thru the mill so that during at least a portion of the rolling operation it is being rolled simultaneously in at least two stands, and maintaining the temperature of the backing roll necks below a point where expansion of a backing roll body induced by heat in the roll neck causes detrimental variation in the product.
11. In the method of rolling thin mate-

rial of substantially uniform thickness in a continuous mill comprising a plurality of stands having working rolls and backing rolls of larger diameter, the steps consisting in passing material successively through the several stands and limiting the rise in temperature of the backing roll necks to such a point that variations in the contour of the backing rolls are controlled within such limits as to substantially prevent buckling or wrinkling of the thin material passed between the working rolls, such as would be consequent upon variation of the contour of the backing rolls in the several stands.

12. A mill for producing thin, wide, rolled material of substantially uniform thickness, comprising a plurality of stands having working rolls and backing rolls of larger diameter, the mill operating to reduce the material to such thinness that its direction of travel between continuous stands could not be controlled by side guides, and anti-friction bearings for the necks of the backing rolls, whereby the contour of the backing rolls in a stand is not varied by roll neck heating to such an extent as to interfere with the proper direction of the material in a substantially direct line to a succeeding stand, the stands being arranged to successively act on the material.

13. A rolling mill comprising a series of stands of rolls arranged to successively engage a piece of material to be rolled, each stand being composed of working rolls, backing rolls of larger diameter, and means for applying power to the working rolls, said mill defining successive passes of such width and effective for taking such drafts that the product of the mill is of such width and thinness that slight variations of roll contour such as would be due to variation arising from change of temperature of the backing roll necks would buckle or wrinkle the piece during its passage through the mill, and anti-friction bearings for the backing rolls whereby such buckling or wrinkling is avoided.

In testimony whereof we have hereunto set our hands.

FLORENCE C. BIGGERT, JR.
LANE JOHNSON.
